COMBINED BELT, PURSE, AND PEN

Aaron Rothchild, Flushing, and Herman B.
Orloff, Yonkers, N. Y.

Application September 2, 1949, Serial No. 4,824

Term of patent 3½ years

(Cl. D3—10)

To all whom it may concern:

Be it known that we, Aaron Rothchild and Herman B. Orloff, both citizens of the United States and residing respectively at Flushing, in the county of Queens and State of New York, and at Yonkers, in the county of Westchester and State of New York, have invented a new, original, and ornamental Design for a Combined Belt, Purse, and Pen, of which the following is a specification, reference being had to the accompanying drawing, forming a part thereof.

Fig. 1 is a front perspective view of a combined belt, purse, and pen, showing our new design.

Fig. 2 is a rear perspective view.

Fig. 3 is a side elevational view thereof partly in section, the section being taken on line 3—3 of Fig. 1.

We claim:

The ornamental design for a combined belt, purse, and pen, substantially as shown.

AARON ROTHCHILD.
HERMAN B. ORLOFF.
